LIFE PRESERVER

Frederick L. Brown, Greenfield, Ohio, assignor to
 The American Pad & Textile Company, Green-
 field, Ohio, a corporation of Ohio

Application June 9, 1943, Serial No. 490,157

1 Claim. (Cl. 9—17)

This invention relates to a life preserver and has for a principal object a simplified construction whereby the life preserver may be worn by a person such as a soldier or sailor, wearing a pack on his back, without disturbing the pack.

Another object is to provide such a life preserver which may be put on or taken off in a fraction of time by a person burdened in the manner described.

Another object is the provision of a device of this kind, which in spite of its simplicity of construction, is highly effective for supporting the wearer in the water, and which is provided with means which render the positioned life preserver substantially non-displaceable.

Another object is to provide a life preserver comprising the features mentioned, which likewise performs the function of turning the wearer from a face downward to a face upward position automatically, without effort on the wearer's part.

These and other objects are attained by the means described herein, and illustrated in the accompanying drawing, in which:

Fig. 1 is a side elevational view of the life preserver of this invention in operative position on a wearer, parts being shown in dotted lines.

Fig. 2 is a front elevational view of the device as seen in Fig. 1.

Fig. 3 is a top plan view of the life preserver.

Fig. 4 is a cross-sectional view on line 4—4 of Fig. 3.

Life preservers heretofore in common use have usually been of the "jacket" type, that is to say, in the general form of a jacket, and therefore put on and taken off in the manner of a jacket. Should the wearer of this older type of jacket have military or other equipment fastened to his body and back, it is obvious that the matter of putting on and wearing this jacket type of life preserver was a matter of some difficulty. Other older types of life preservers involved similar difficulties or else failed to maintain their position and properly perform their function.

The present invention overcomes difficulties such as those described by the provision in the life preserver of the advantages mentioned briefly in the objects above, that is to say, a life preserver which may be instantly donned by a person carrying full military equipment; which performs effectively the life preserving function, including the turning of a possibly unconscious wearer to a face upward position; and which preserver may be instantly removed after

use by simply throwing the preserver backwardly over the shoulders.

In greater detail and with reference to the drawing, the life preserver comprises three principal parts, namely, a pair of buoyant tunnel members 5 and 6 joined at their upper ends, in generally parallel relationship, by a buoyant neck member 7.

The tunnel members 5 and 6 are preferably formed of a durable covering material 8, such as canvas, filled with a stuffing 9, such as kapok. The lower portions of the tunnel members may be substantially straight as seen in Fig. 3 and the upper portions curved. The latter are joined as at 10, Fig. 4, to the edge seam of the neck member 7. The latter is a cushion-like structure and in outline may be substantially rectangular as seen in Fig. 3. Similarly to the tunnel members, the neck member is formed of canvas-like covering material 13 and kapok or similar stuffing 14. The neck member may be centrally constricted such as by the tuck 11, Fig. 3, to provide a curved neck portion 12. At the sides of this neck portion 12, the tunnel members 5 and 6 are connected to the neck member, which connection, together with the curved form of the upper portions of the tunnel members, results in the latter converging inwardly toward one another adjacent their upper portions, to form a substantially V-shaped neck opening. At the same time, the lower portions of the tunnel members, as seen in Fig. 3, diverge from one another to some extent in the flat position of the life preserver. However, when the latter is put on the wearer, this divergence disappears and the tunnel members assume a parallel position, as will be further described.

Each of the rear corners of the neck member 7 has a strap 15 and 16, respectively, secured thereto. The lower portion of one of the tunnel members such as the member 6, has an adjustable strap 17 secured thereto as at 18, adjacent one end of the strap. The end of the strap 17, 45 adjacent the securing point 18, has a buckle or ring 23 connected thereto, and the opposite free end of the strap has the snap hook 22 secured thereto. Strap guide 19 is provided on the opposite tunnel member 5.

The life preserver is put on by placing the neck member 7 at the back of the wearer's neck, with the tunnel members extending down the front of the wearer. It will be seen in Fig. 1 that the neck member 7 in no way interferes with a pack or knapsack, indicated generally at 20, carried

on the back of the person wearing the life preserver. The straps 15 and 16, hanging downwardly from the rear corners of the neck member 7, are each carried under the adjacent arm of the wearer and tied across the tunnel members 5 and 6, at the front, as shown at 21, Figs. 1 and 2. This tying of the strap members 15 and 16 constricts or concentrates the tunnel members 5 and 6 along the central portions of the front of the wearer, which central positioning is important in achieving the turning-over function of the life preserver, as will be further referred to.

The neck member 7 fits well up around the back of the wearer's neck and readily conforms thereto by reason of the curved neck portion 12 and the pulling together of the tunnel members at the front. The tuck 11 also tends to form a kind of crotch in which the wearer's head is well supported against turning or lolling to one side or the other, as in a case where the wearer might be unconscious.

The adjustable strap 17 which, of course, has previously been properly adjusted to the individual wearer's requirement, is now carried around the back of the wearer and the free end passed through the guide 19. Thereafter the hook 22 is snapped on to the cooperating buckle or ring 23 on the opposite tunnel member for further holding the tunnel members in place. The engaged position of the hook 22 and buckle 23 is seen in Fig. 2.

As already stated, the life preserver in no way interferes with the equipment carried by the wearer, and may be donned in a fraction of time. When the life preserver is taken off, the upper strap connection 21 is undone and the hook 22 released, whereupon the tunnel members may simply be thrown backwardly over the shoulders of the wearer for completely releasing the preserver.

It is obvious that the facility of positioning and removal of the life preserver and its novel structure, permitting the maximum equipment to be carried without interfering with the use of the preserver, are all highly important factors under modern usage, and particularly modern warfare where disembarkments, whether by design or by necessity, are frequent.

It is important to note that the central positioning of the tunnel members down the front of the wearer results in concentrating the buoyant material in such manner that should the wearer be unconscious, or should he desire to rest from swimming, or treading water, the tunnel members in a fraction of time automatically turn the wearer upon his back with his head supported well out of the water by the neck member 7. It may be remarked that prior life preservers in which the buoyant material was

disposed in more or less flat position over the front of the wearer, failed to perform this turning-over function, since the wearer was simply supported by this front buoyant material, as on a raft, a position which might well prove fatal, should the wearer, as frequently happens, be unconscious. The present life preserver, on the other hand, renders the face down position of the wearer unstable so that he is almost immediately turned over onto his back without effort on his part when he so desires, or when, due to unconsciousness, he is unable to control his position. The upper and lower straps prevent accidental displacement of the life preserver, and the upper straps 15 and 16 passing across the arm-pits of the wearer, effectively preclude the life preserver from working upwardly out of position. The strap 17 is preferably of such strength as to be utilized for lifting the wearer of the life-preserver thereby, it being contemplated that a hook or the like may be used for engaging the strap 17 for lifting the wearer, as for example, in cases of emergency.

Variations will suggest themselves upon consideration of the means disclosed herein, but these are believed to be comprised within the spirit and scope of the invention.

What is claimed is

A life preserver comprising a buoyant back member, elliptical in longitudinal cross-section and extending transversely across the upper portion only of a wearer's back, said back member having a centrally disposed concave portion in its front marginal edge for engaging the back of the wearer's neck; two spaced, independent, buoyant tunnel members each having a reduced upper part and a rounded body portion in transverse cross-section and of substantially equal transverse extent throughout its entire length; narrow hinge portions of reduced thickness disposed on opposite sides of the concave portion and each hinge portion joining the upper reduced edge of a tunnel member to the back member, the opposed side edges of the upper portions of the tunnel members converging outwardly from the hinge portions on smooth curves to form, with the concave portion, a close fitting neck opening, said opposed edges thereafter diverging from the neck opening to the free ends of the tunnel members when the preserver is in a flat condition, to provide, in wearing position, abutting members which extend down the central front part of the wearer; and straps fastened to the rear corners of the back member and each extending beneath the wearer's arm and across the tunnel members for maintaining the tunnel members in the said wearing position.
